UNITED STATES PATENT OFFICE.

WILLIAM EVE ZACHRY, OF NEW YORK, N. Y., ASSIGNOR TO HIMSELF AND
WALTER E. COONEY, OF BROOKLYN, NEW YORK.

CAR-FENDER.

SPECIFICATION forming part of Letters Patent No. 726,390, dated April 28, 1903.

Application filed October 27, 1902. Serial No. 128,865. (No model.)

To all whom it may concern:

Be it known that I, WILLIAM EVE ZACHRY, a citizen of the United States, residing at New York, in the county of New York and State 5 of New York, have invented certain new and useful Improvements in Car-Fenders, of which the following is a specification.

My invention relates to car-fenders of the class where there is a forward guard and a 10 rear catching appliance, the object being to provide a device of this character of simple and inexpensive construction which will serve as an effective guard against accident.

The invention comprises a fender consisting of two coöperating members, one being 15 permanently attached below the car and the other detachably supported in front of the car-platform and so connected to the rear member as to cause the latter to be thrown 20 downward in contact with the ground when the front member strikes an obstruction.

The construction of the improved fender will be fully described hereinafter in connection with the accompanying drawings, which 25 form part of this specification, and its novel features will be particularly pointed out in the appended claim.

In the drawings, Figure 1 is a side elevation of one end of a car with my improved 30 fender applied thereto, the normal position of the fender being shown in full lines and its position when an obstruction is met being shown in dotted lines. Fig. 2 is a front elevation of the improved fender in its normal 35 position.

Corresponding parts in both figures are denoted by the same reference characters.

The reference-numeral 1 designates the front platform of the car. Beneath each side 40 of the floor of the car depends a bracket 2, said brackets being formed with bearings for a shaft 3.

4 designates the rear member of the fender, comprising a frame, the forward portion 5 of which is projected forward and is netted 45 with wire or other suitable yielding material. At each side of the frame 4, near the upper end thereof, is a lug 6, said lugs projecting forward and formed with openings through 50 which the shaft 3 extends. The frame 4 is

also provided at one side, adjacent to the lug at that side, with a ratchet-wheel 7, adapted to be engaged by a spring-pawl 8, depending from the undersurface of the car-floor. The upper portion of the frame 4 is connected at 55 each side to the car-body by helical springs 9, which urge the fender-frame 4 in the position shown in full lines in Fig. 1. Attached to each side of and projecting forwardly of the rear fender 4 is an arm 10, loosely connected at its front end to a rearwardly-extending rod 11 by a shackle 12, depending from the end of the arm 10. A shoulder 13 on the rod 11 engages the forward face of the shackle 12. At the forward end of each of the arms 10 is 60 a loop or eye 14, which is pivoted to lugs 15, extending from and near the lower ends of the side bars of the front member 16 of the frame. The front member 16 comprises a frame bent to concavo-convex form and filled 65 in with a suitable netting. The upper portion of the front member 16 is suspended from hooks 17, projecting upward from the front of the car-platform.

The utility and operation of the fender will 70 be readily understood and appreciated. Ordinarily the two members of the fender are in the position shown in full lines in Fig. 1, both of the members being clear of the ground. When the front member 16 contacts an ob- 75 struction—as, for example, a human body—the said member is forced rearwardly, and by means of the rods 11 and 10 the rear member 4 is thrown down to the position shown by 80 dotted lines in Fig. 1 and will be retained in 85 such position by the spring-pawl 8, thus effectually preventing the body or other obstruction from passing under the car-wheels. When the pawl is released from the teeth of the ratchet-wheel 3, the front and rear mem- 90 bers will be returned to their ordinary posi- 95 tions by means of the springs 9.

It will be apparent that the front member 16 may be readily removed from the supporting-hooks 17 and either disconnected at the 95 point 15 from the rods 11 or these rods themselves may be withdrawn from the shackles 12 and the guard member 16 thus permitted to be transferred to connection with a corresponding rear member 4 at the opposite end 100.

of the car when the latter returns upon a line with the reverse end foremost or when it is out of commission.

I would have it understood that the invention is not restricted to all of the details shown in the drawings, but includes all such modifications and variations as may fall within the scope of the following claim.

Having thus described my invention, I claim and desire to secure by Letters Patent—

A car-fender composed, essentially, of the following instrumentalities in combination, viz: a front member constituting a guard consisting of a netted frame having its side bars suspended and detachable from the front of the car-platform, rods pivoted near the lower ends of said side bars and extending rearwardly, a rear member constituting a catch-

ing appliance made up of a netted frame having downwardly and forwardly curved side arms, and forwardly-projecting rods loosely shackled to the rearwardly-extending rods of the front member, a spring acting upon the rear member and operating to keep it in its normal position clear of the ground, and to also maintain the front guard in its normal relation to the car, a ratchet carried by the rear member, and a spring-pawl normally out of operative engagement therewith, all substantially as set forth.

In testimony whereof I have signed my name in the presence of the subscribing witnesses.

WM. EVE ZACHRY.
